UNITED STATES PATENT OFFICE

2,464,670

RECEPTACLE COVER OPERATOR
AND LOCK

Carl Hilbert Carlson, Chicago, Ill.

Application September 1, 1944, Serial No. 552,336

1 Claim. (Cl. 268—74)

1

This invention relates to improvements in receptacle cover locks and more particularly to a garbage receptacle cover locking device which, however, is capable of application to a variety of types of receptacle covers.

One object is to provide a receptacle cover lock that may be manufactured along with the receptacle with which it is associated or that may be made separately and installed upon various types of receptacles after same have been in use.

A further object is to provide a receptacle cover lock that is rat and vermin proof and therefore sanitary in use. A still further object is to provide a cover lock for receptacles that is proof against tampering by unauthorized persons.

A still further object is to provide a receptacle cover lock that is durable in use, inexpensive to manufacture, composed of few parts and not likely to get out of order, that is shielded, but one wherein the operating parts are readily accessible so that repair or replacement when necessary may be readily made.

With the foregoing and other objects in view the invention consists in the combination and arrangement of parts to be hereinafter fully described, pointed out in the claim and illustrated in the accompanying drawing that forms a part of this patent, and in which—

Fig. 1 is a view in perspective of a receptacle provided with a hinged cover and with the instant locking device which is not disclosed in this view but which is fully shown in the following views.

Fig. 2 is a vertical substantially central sectional view through the receptacle and cover of Fig. 1 but in open position, illustrating the cover locking mechanism.

Fig. 3 is a fragmentary sectional view similar to Fig. 2 but with the movable parts in an altered or closed position.

Fig. 4 is a view of the locking mechanism in elevation, taken on the line 4—4 of Fig. 3, and

Fig. 5 is a vertical cross sectional view through the receptacle proper, at right angles to that shown in Fig. 2.

Like reference characters denote corresponding parts throughout the several views.

The reference numeral 1 denotes the receptacle body provided with the usual discharge opening 2 upon opposite sides of and rising above which are the ways 3 for the sliding door 4 provided with the perforated lug 5 for engagement by the hook 6 secured thereabove to the receptacle wall by the screw eye 7. The receptacle is provided also with the orifice 8 having the angular metal facing 9 to which is secured the bracket 10 de-

2

pending into the receptacle and formed or provided with a perforate ledge 11 horizontally disposed and extending longitudinally of said orifice.

5 Journalled in bearings 12 in the side walls of the receptacle and extending through said bracket 10 is the shaft 13, the ends of said shaft being squared for engagement with the notched end of the key or handle 14 which is inserted in wall 10 perforations for engagement with the countersunk shaft ends. Fast upon shaft 13 is the primary lever 15 connected by link 16 to the secondary lever 17 intermediate its ends, one end of said lever 17 being bifurcated and secured by 15 pin 18 to bracket 10, said lever at its opposite end being pivotally secured to a primary lever 19 pivoted to an ear 20 depending from the inner face of the cover 21 pivoted to ears 22, said cover having downturned flanges 23 that in the closed position of said cover fit snugly about the orifice making the receptacle rat and vermin proof.

Referring again to said lever 15 same carries a spur 24 to which one end of a contractile spring 25 is secured that is connected to a cord 26 that 25 passes about a peripherally recessed guide roller 27 the axis of which is secured to said bracket 10, said cord then being secured to the shank 28 of a bolt 29 slidably arranged within the bolt casing 30 secured to said bracket 10 and to ledge 11. The shank 28 extends through a perforation in one end of said bolt casing while the free end of said bolt is movable through a perforation at the opposite end of said casing, said shank in its movement passing between the prongs of said lever 17 and having disposed thereabout within said 35 casing 30 the coil spring 31 one end of which abuts said bolt and the opposite the adjacent end of said casing.

In Figs. 2 and 5 of the drawing the cover 21 is shown in wide open position, said cover having secured thereto the keeper 32 perforated for reception of the bolt 29. As the cover is moved manually to closed position the levers 19, 17, link 16 and lever 15 rotate shaft 13 and relieve tension of spring 25 and permit spring 31 to expand and urge the bolt 29 outwardly with respect to casing 30 and, as the keeper is moved into line therewith, to enter the keeper perforation and lock said cover in closed position. An effort manually to raise the cover now will fail due to the presence of bolt 29 in keeper 32, said keeper exerting an upward and binding pull against said bolt. The cover can now only be opened by applying the handle to one end of the 55 shaft 13 to rotate same and raise lever 15 with

its connections to said cover, movement of lever 15 expanding spring 25 through the medium of cord 26 and shank 28 retracting bolt 29 against the tension of spring 31 to free the keeper 32 allowing the cover to be moved upwardly, the upward movement of lever 17 causing it to contact ledge 11 and arrest the opening movement of said cover in substantially wide open position disclosed in Fig. 2.

A detachable shield plate 33 formed with lateral flanges secured to ledge 11 and facing 9 depends from the orifice into the interior of the receptacle alongside the locking mechanism to protect same from the material received thereto and protecting said mechanism from tampering while the cover is in an open position, said plate flange being perforated to receive pins whereby to connect it to correspondingly perforated portions of said ledge, said plate being formed of resilient material, the end flange being pressed into binding engagement with the orifice facing when the plate is in operative position.

The flange 34 is disposed horizontally to lie flat upon the said ledge 11 when its perforations will be disposed in register with like perforations in said ledge to receive pins 35 to retain said plate in operative but readily movable position, the flange 36 formed upon one upper corner of said plate being vertically disposed and bent laterally in a position parallel with said facing at this point against which facing said flange is somewhat tightly pressed when flange 34 and ledge 11 are in engaged relation.

What is claimed is:

In a receptacle cover lock, an oblong body having a top formed with an orifice, a cover hinged to said top at said orifice movable longitudinally of said body, a bracket depending from said cover into said body at said orifice, a rotary shaft extending transversely of said body through said bracket forwardly of the hinge-point of said cover, a ledge integral with said bracket extending longitudinally of said orifice, a lever connection between said cover and bracket passing through

said orifice for engagement with said ledge as said cover assumes wide open position, the ends of said lever connection disposed upon opposite sides of said rotary shaft in the wide open cover position, a keeper carried by and disposed normal to said cover and in the closed cover position disposed substantially wholly within the body, a bolt casing within the body in line with and contiguous to said keeper in the closed cover position, a sliding bolt in said casing for engagement with said keeper, a spring within said bolt casing connecting same and said bolt for yielding projecting same through one end of said casing into engagement with said keeper, a lever fast to said rotary shaft, a spur carried by said lever, a link connecting said lever and the aforesaid lever connection, a resilient connection between said spur and sliding bolt, and a handle for removable operative engagement with said rotary shaft to transmit an opening movement to said cover.
